POLE CLIMBER

Robert J. Miller, Franklin, Pa.

Application September 25, 1948, Serial No. 51,149

8 Claims. (Cl. 227—27)

1

This invention relates to pole climbers of the type having a removable gaff and a shank portion longitudinally adjustable for different leg lengths.

The prime object of the invention is to provide a climber of the type indicated in which the gaff may be readily interchanged and locked in position without the use of special tools. An allied object is to provide a gaff locking means which will operate positively to lock the gaff in position. Another object is to provide a gaff locking means which can be readily manipulated to free the gaff or to lock it in position.

Another important object is to provide means for adjusting the leg length of the shank of the climber, which will be positive in action and yet easy to operate in adjusting the shank.

For the attainment of the foregoing and such other objects as may appear or be pointed out herein, I have shown a preferred embodiment of my invention in the accompanying drawing, wherein:

Fig. 1 is a front view of the improved climber;

Fig. 2 is a sectional elevation through the entire climber, taken on the line 2—2 of Fig. 1, the gaff being omitted;

Fig. 3 is a sectional elevation similar to Fig. 2 but showing only a portion of the climber, the gaff being shown both in place (solid lines) and being inserted (dot-and-dash lines);

Fig. 4 is a rear view of the gaff, that is, as seen from the rear or left of the climber, Fig. 3;

Fig. 5 is a fragmentary sectional elevation similar to Fig. 3, also showing the wedge being inserted;

Fig. 6 is a perspective view of the wedge;

Fig. 7 is a sectional view similar to Fig. 5, but showing the wedge fully inserted to home position;

Fig. 8 is a transverse section taken on the line 8—8 of Fig. 1; and

Fig. 9 is a cross-section through the gaff taken on line 9—9 of Fig. 3.

The improved climber comprises a shank or leg portion 10 and a foot or stirrup portion 20. It will be understood that the stirrup 20 is fitted between the heel and sole of the user's shoe, with the shank 10 adjacent his leg. The climber is secured to the leg by straps both at the shank portion 20 and stirrup or foot portion 10. The end of stirrup 10 is formed as a loop 16 for the ends of the foot strap (not shown) while the ends of the leg strap (not shown) are secured to loops 21, 22 at the upper end of shank 20. This strap is usually disposed at a point just below the knee; in order that the shank portion may

2

be accommodated for different leg lengths, the upper portion of the shank is made longitudinally adjustable. That is, the strap loops 21, 22 are not secured to shank portion 20 but to a shank slide 23 which is slidably mounted on shank 20.

Shank slide 23 is formed of a flat front plate 24 and a body plate 25 which is shaped to form with flat front plate 24, the trapezium hollow shape shown in Fig. 8. As there shown, and also in Fig. 1, the edges of the body plate 25 are turned inwardly to form flanges 25^x, over the front flat plate 24. The shape of shank slide 23 is such that it is snugly fitted over the shank 20, which is (see especially Fig. 8) channel-shaped with outwardly spread legs 20', 20'. Front plate 24 is provided with a pair of opposed portions 26, 26 (Fig. 1) which are formed to provide ears for the strap loops 21, 22.

Shank slide 23 may thus be slid along shank 20 to extend or shorten the effective length of the shank or leg portion of the climber. Slide 23 may be secured in any adjusted position by means of a small screw bolt 7 having a flat head which may be screwed in a tapped hole (Fig. 2) provided in a thickened boss 28 of the shank 20. Flat plate 24 has a plurality of holes 27, (Fig. 1) through which bolt 7 may be inserted, these holes being countersunk to neatly receive the flat head of the bolt. Thus, by selecting the proper one of the holes 27 and inserting bolt 7 therein for screwing engagement in tapped hole 28, the shank or leg portion of the climber may be adjusted to the proper length.

The gaff 30 of the improved climber is separately shown in Fig. 4, but its shape may be best described with reference to either one of Figs. 3, 5, 7. From the latter figure it will be seen that gaff 30 has what might be termed a girth portion 31 which is that portion of the gaff having the greatest cross section or girth; this cross-section of girth 31 is shown in Fig. 9. It presents a flat "inside" edge 32; by "inside" is meant that, when the gaff is in position on the climber (as in Fig. 5) this edge or side 32 of the gaff faces inwardly or toward the leg or shoe of the user. The outer edge of the gaff at girth 31 (Fig. 9) is curved as shown at 34, while the two sides 33 are flat or straight. The blade 35 of the gaff extends downwardly from its girth portion 31 and is tapered both in an inside-outside sense (Fig. 7) and frontally (Fig. 4) towards a point as shown in both figures.

Extending upwardly from its girth portion 31, the gaff has a tang 36, the sides 33^x are flat like the sides 33, 33 at the girth 31, see Fig. 9, but

which taper towards one another upwardly as shown in Fig. 4, so that the tip 37 of the tang 36 is somewhat narrower than girth 31 of the gaff 30. The "inside" (defined as above) of tang 36 is contoured, when in place in the climber, as in Fig. 5, to the inside contour of the climber, except its tip end 37, Fig. 5, is slightly tapered at 37^x. The "outside" of tang 36, on the other hand, is shaped entirely different from the outside contour of the climber. In the first place, it will be observed, best from Fig. 5, that the tip 37 of tang 36 presents a flat facet 37' which, when the gaff is in position, as it is in said figure, facet 37' will be substantially flush with the outside surface of the climber. It will also be observed that this facet 37' is substantially on the same line (plane) as the outside of gaff blade 35, which, as described above, is tapered from the "inside" towards the "outside" (as defined above).

Between tip facet 37' and girth 31, tang 36 is recessed at its "outside" to form an extended recess 38 (see Fig. 3) and a limited recess or groove 39, so as to present a ridge 39^x between groove 39 and the extended recess 38 which extends from ridge 39^x to top facet 37'.

The lower portion of shank 20 is provided with openings, recesses and the like for receiving gaff 30. In the first place, shank 20 is provided with an opening 11 near the stirrup 10 of the climber which opening extends through the web 14 of the channel-shaped shank. As best seen in Fig. 2, opening 11 extends between the legs or flanges 20' of the channel-shaped shank 20 and pierces its web 14 to present an opening which by reason of the fact that the shank 20 curves at this point into the stirrup 10, is directed downwardly through web 14 of the climber. Opening 11 has flat sides 13, 13 which taper inwardly from opening 11 upwardly, as best seen in Fig. 1, which taper corresponds to that of the sides 33^x, 33^x of the gaff (see Fig. 4). Tip 37 of the gaff, which is narrower than its girth 31 and the opening 11, is inserted therein, (see Fig. 3, where it is shown in dot-and-dash lines in its preliminary position) and pushed upwardly. Shank 20 is provided with a second (smaller) hole 17 spaced upwardly from the first-mentioned opening 11, oriented "outwardly" (as defined above) through web 14 of the climber. As the gaff 30, inserted first through larger, lower opening 11, is pushed upwardly, tip 37 of its tang 36 is received in upper, smaller hole 17. To guide tip 37 into hole 17, the web 14 of the shank is provided with a lip 17^x disposed at the upper limit of hole 17 and upwardly inclined to contact inclined tip 37^x of the tang (see Fig. 3) to guide the same through hole 17.

The web 14 of the climber is provided with a transverse rib 19 which is snugly received in groove 39. The gaff is inserted through lower opening 11 with its tip 37 being directed by lip 17^x into upper hole 17. When the gaff is fully in home position, with facet 37' of the gaff tip flush with the outside surface of the shank portion, rib 19 of the climber will have been received in groove 38 of the gaff.

To lock the gaff 30 in this position, use is made of a small wedge piece 40, Fig. 6, which has a flat "inside" face 49 (as defined above) and likewise a flat "outside" face 48. The inside face 49 is tapered, 49^x, to a narrow leading edge, and the leading portion is recessed at 47 to provide two leading tips 46, 46 narrow in thickness and width. Wedge piece 40 is inserted, after the gaff is in place, as described, into the lower opening,

more particularly between the inside surface 32 of the gaff and the edge 15 of opening 11 (see Figs. 5 and 2). Edge piece 40 is shown in Fig. 5 as it is being inserted, with its face 49 on the "inside" (as defined above). It is shown in Fig. 7, fully pushed home; it will be seen from this figure that the inside face 49 of the wedge is tapered, at 49^x, so that it will conform to the contour of the inside of the climber. It will be noted, Figs. 5 or 7, that side 15 of the gaff opening is substantially parallel to the inside surface 32 of the gaff, so that wedge or key 40 can be easily inserted in place and guided between 32, 32.

Wedge piece or key 40 is tapered outwardly from its rear end 41 to its leading tips 46, 46, as clearly seen in Fig. 6. Key or wedge piece 40 is made of dead soft anneal steel so that it can be deformed without too great force. As the key is forced into place, its leading tips 46, 46 are compressed toward each other to firmly grip the key in place, thus locking the gaff in the climber. The wedge or key is driven home without the use of any special tool, a screw-driver and hammer being sufficient. The key may be driven out by the same tools, but in this case, the tip of the screw-driver is inserted from the "inside" of the climber, to reach the tip end of the wedge in opening 11.

I claim:

1. In a climber, the combination of a body member having a shank portion and a stirrup portion, said shank portion being channel-shaped and provided with a lower opening near the juncture with the stirrup portion oriented downwardly through the web of the channel and an upper, smaller hole opening outwardly through the web, a gaff having a girth portion presenting a flat inside surface and flat sides, a blade tapered downwardly from said girth portion, and a tang tapering upwardly from said girth portion to a narrow tip, said tip outwardly presenting a flat facet, the flanges of said shank channel tapering upwardly from said lower opening to narrow the channel at said upper hole, the tang being inserted through the lower opening to present its said tip facet through the upper hole and substantially flush with the outside surface of the shank, said tang having a transverse groove near said girth portion of the gaff, the web of the shank channel having a transverse rib at its said lower opening, said rib being received in said groove of the gaff, when inserted as aforesaid, the edge of the lower opening adjacent the stirrup portion presenting a flat surface substantially parallel to said flat inside surface of the gaff girth, and a key having parallel flat surfaces inserted in said lower opening between said flat inside surface of the gaff girth and said flat surface edge of the lower opening.

2. The climber according to claim 1 wherein said shank is provided with an inclined lip at the upper edge of said upper hole to guide the gaff tip therethrough.

3. In a climber, the combination of a body member having a shank portion and a stirrup portion, said shank portion being channel-shaped and provided with a lower opening near the juncture with the stirrup portion oriented downwardly through the web of the channel and an upper, smaller hole opening outwardly through the web, a gaff having a girth portion presenting a flat inside surface and flat sides, a blade tapered downwardly from said girth portion, and a tang tapering upwardly from said girth portion to a

narrow tip, the flanges of said shank channel tapering upwardly from said lower opening to narrow the channel at said upper hole, the tang being inserted through the lower opening to present its said tip through the upper hole, said tang having a transverse groove near said girth portion of the gaff, the web of the shank channel having a transverse rib at its said lower opening, said rib being received in said groove of the gaff when inserted as aforesaid, the edge of the lower opening adjacent the stirrup portion presenting a flat surface substantially parallel to said flat inside surface of the gaff girth, and a key having parallel flat surfaces inserted in said lower opening between said flat inside surface of the gaff girth and said flat surface edge of the lower opening.

4. The climber according to claim 3 wherein the inside flat surface of the key is beveled to conform, when fully inserted as aforesaid, with the inside contour of the climber.

5. The climber according to claim 4 wherein the upper portion of the key including its said bevel is centrally recessed to present a pair of thinned and narrowed tips.

6. The climber according to claim 5 wherein said key is made of soft annealed steel whereby its said tips are deformed when inserted as aforesaid, to lock the gaff in place.

7. In a climber, the combination of a body member having a shank portion and a stirrup portion, said shank portion being channel-shaped and provided with a lower opening near the juncture with the stirrup portion oriented downwardly through the web of the channel and an upper, smaller hole opening outwardly through the web, a gaff having a girth portion presenting a flat inside surface and flat sides, a blade tapered downwardly from said girth portion, and a tang tapering upwardly from said girth portion to a narrow tip, the flanges of said shank channel tapering upwardly from said lower opening to narrow the channel at said upper hole, the tang being inserted through the lower opening to pre-

sent its said tip through the upper hole, said tang having a transverse groove near said girth portion of the gaff, the web of the shank channel having a transverse rib at its said lower opening, the rib being received in said groove of the gaff when inserted as aforesaid, and a key having parallel flat surfaces inserted in said lower opening to lock the gaff in place.

8. In a climber, the combination of a body member having a shank portion and a stirrup portion, said shank portion being channel-shaped and provided with a lower opening near the juncture with the stirrup portion oriented downwardly through the web of the channel and an upper, smaller hole opening outwardly through the web, a gaff having a girth portion presenting a flat inside surface and flat sides, a blade tapered downwardly from said girth portion, and a tang tapering upwardly from said girth portion to a narrow tip, the flanges of said shank channel tapering upwardly from said lower opening to narrow the channel at said upper hole, the tang being inserted through the lower opening to present its said tip through the upper hole, said tang having a transverse groove near said girth portion of the gaff, the web of the shank channel having a transverse rib at its said lower opening, the rib being received in the groove of the gaff when inserted as aforesaid.
